US0D1108598S

(12) **United States Design Patent** (10) **Patent No.:** **US D1,108,598 S**
(45) **Date of Patent:** **** Jan. 6, 2026**

(54) **MULTI-PANEL AIR FILTER**

(71) Applicant: **K&N Engineering, Inc.**, Riverside, CA (US)

(72) Inventors: **Jere James Wall**, Helendale, CA (US); **Steve Williams**, Cherry Valley, CA (US)

(73) Assignee: **K&N Engineering, Inc.**, Corona, CA (US)

(**) Term: **15 Years**

(21) Appl. No.: **29/907,011**

(22) Filed: **Jan. 3, 2024**

(51) **LOC (15) Cl.** **23-04**

(52) **U.S. Cl.**

USPC **D23/365**

(58) **Field of Classification Search**

USPC D23/209, 322, 323, 324, 325, 332, 333, D23/336, 341, 351, 352, 353, 354, 355, D23/358, 364, 365, 366, 368, 370, 371, D23/393; D32/30; D24/162; D7/400

CLAIM

The ornamental design for a multi-panel air filter, as shown and described.

DESCRIPTION

FIG. 1—Top, front, right side perspective view

FIG. 2—Front elevation view;

FIG. 3—Rear elevation view;

FIG. 4—Right side elevation view;

FIG. 5—Left side elevation view;

FIG. 6—Top plan view; and,

FIG. 7—Bottom plan view.

The broken lines shown in figures are for the purpose of illustrating portions of the multi-panel air filter and form no part of the claimed design.
